UNITED STATES PATENT OFFICE.

ANDREW G. SEA, OF CHICAGO, ILLINOIS.

BUILDING FORM.

Application filed May 26, 1922. Serial No. 563,851.

To all whom it may concern:

Be it known that I, ANDREW G. SEA, a citizen of Sweden, residing at Chicago, in the county of Cook and State of Illinois, 5 have invented new and useful Improvements in Building Forms, of which the following is a specification.

This invention relates to building forms particularly designed for use in the construction of buildings and building walls as disclosed in my application for wall construction, filed June 4, 1921, Serial No. 474,900, and an object of the invention is to provide a novel form of building form construction which is simple and durable and may be easily built up and torn down, so as to permit its continued use, thereby saving material expense such as occasioned by the building and tearing down of wooden forms 20 which can be used only a few times until they are either broken up or mutilated so as to prevent further use.

A further object of this invention is to provide a building form structure as specified which is used in combination with the studs of building construction or wall for providing forms in which concrete or cementitious material may be poured.

Other objects of the invention will appear 30 in the following detailed description taken in connection with the accompanying drawings wherein:

Fig. 1 is a side elevation of the improved form.

Fig. 2 is a horizontal section taken on the line 2—2 of Fig. 1.

Fig. 3 is a vertical section through the forms in place.

Fig. 4 is a perspective view of a part of the 40 form used in forming window ledges.

Fig. 5 is a side elevation of a modified form of the form.

Fig. 6 is a vertical section on the line 6—6 of Fig. 5.

Referring more particularly to the drawings, the improved building forms are provided for use in connection with the studs A of a building structure for forming the spaces for receiving the cementitious material of which the walls of the building are made and the form structures comprises plates 1 which are substantially U shaped in cross section and are adapted to have their relatively short legs 2 placed in abutting engagement with adjacent studs A to which

studs the plate 1 is attached by means of nails 3 of the usual type such as used in building construction. It is to be understood that the plates 1 are constructed of sheet metal and that they are provided with suitable openings for receiving the nails 3 to securely attach the plates 1 in place. The plates 1 are substantially U shaped in cross section so as to provide the air spaces between the outer walls and the inner wall surfaces, such air spaces being shown in my wall construction application previously referred to.

The outer side of the frames are formed by flat plates 4 formed of sheet metal and which are provided with openings 5, adjacent one edge and with spaced slots 6 at their opposite edges. The openings 5 are adapted to receive nails 7 which are driven into the studs A, and in starting the construction of a form for building a wall therein, the corner forming plate 9 is attached to the stud A at one end of the wall and this corner plate 9 is constructed of sheet metal bent to provide right angularly disposed portions. The corner plate 9 is spaced the proper distance from the studs A, by nails 10 which are previously driven into the stud, having their heads 11 spaced the proper distance from the studs so that when the corner plate 9 is placed in the beginning of the construction of the form, it is held in proper spaced relation from the stud A by the nails 10 and it is attached to the corner stud A by spikes or nails 12 which are driven through suitable openings 13 formed in the corner plate. Flanged sleeves or heads 12' are mounted upon the spikes or nails 12 to facilitate their withdrawal from the studs A. The first flat plate 4 is then positioned with the slots 6 receiving or engaging over the spikes or nails 12 after which the opposite edge of the plate 4 is attached to the end stud by the spikes or nails 7. It is to be understood that the edge of the plate 4 which is attached to the second stud is held in proper spaced relation from the stud by nails or spikes driven the proper distance into the stud for holding the edge of the plate which is provided with the openings 5 at the same distance from the stud as the corner plate 9 is supported. The plates 4 are successively connected to each other and to the studs in the manner as above specified forming a secure, simple, easily constructed and knock down and readily portable form

110

structure to be used in building walls of cementitious materials.

In Fig. 4 of the drawings the forms are shown which are used in the construction 5 of window sills and these forms comprise sections 15 and 16 each of which is constructed of a sheet of metal and is provided with nail receiving openings 17 for attaching them to the skeleton of the building 10 structure and which are further provided with transversely extending portions 19 to provide the necessary thickness or depth to the window ledge.

In Figs. 5 and 6 a slight modification of 15 the inner wall forming plate structure is shown. In standard building constructions, the studs A are all placed at the same distance but it frequently occurs that owing to the particular construction of the wall 20 that some of the studs must be closer together or farther apart than the standard and in such cases the plate structure 1 would not fit properly and to accommodate such conditions the modified structure shown in 25 Figs. 5 and 6 of the drawings has been provided. This modified structure comprises plates 20 and 21 each of which has one of its edges bent transversely to provide the transverse edge 22 which corresponds to the 30 edge or leg portion 2 of the plate 1. The plate 20 is provided with slots 23 extending thereinto from its flat edge and these slots are adapted to receive bolts 24 which are carried by the plate 21. Clamping wing 35 nuts 25 are mounted upon the bolts 24 and are adapted to be threaded upon the bolts to securely clamp the plates 20 and 21 together. By loosening the wing nuts on the bolts and shifting the plates 20 and 21 relative to each other, the bolts moving in the 40 slots 23 the distance between the angle edges 22 of the plates may be varied to properly

engage spaced studs and to form the inner side of the form structure.

It is, of course, to be understood that the 45 invention may be constructed in other manners and the parts associated in different relations and, therefore, I do not desire to be limited in any manner except as set forth in the claims hereunto appended. 50

Having thus described my invention what I claim is:

1. In a building form, corner forming plates provided with spaced nail receiving openings adjacent one of their side edges, 55 and with slots at their opposite edge, said slots adapted to engage other nails used on the adjacent plate in a form construction, and plates substantially U shaped in cross section for forming the inner sides of the 60 form.

2. In a building form, corner forming plates provided with spaced nail receiving openings adjacent one of their side edges and with slots at their opposite edge, said 65 slots adapted to engage other nails used on the adjacent plate in a form construction, plates substantially U shaped in cross section for forming the inner sides of the form, said inner side forming plates composed of 70 a pair of adjustably connected plates to permit adjustment of the active width of the inner side forming plate.

3. In a building form, corner forming plates provided with spaced nail receiving 75 openings adjacent one of their side edges, and with slots at their opposite edge, said slots adapted to engage other nails used on the adjacent plate in a form construction, and means for supporting said plates in 80 proper spaced relation from the wall studs.

In testimony whereof I affix my signature.

ANDREW G. SEA.
